UNITED STATES PATENT OFFICE.

RUDOLPH HOFFMAN, OF CLEVELAND, OHIO.

BURNER.

Application filed April 8, 1926. Serial No. 100,638.

This invention relates to oil burners and more particularly to improvements for devices automatically locking the flame-spreader unit in the wick tube.

It is one of the objects of the invention to provide a comparative simple and inexpensive form of device that will be capable of automatically locking the flame-spreader, when it is inserted in the wick tube, and also capable of being released to permit the removal of the flame-spreader unit.

Other objects of the invention and the features of novelty will be apparent from the following description in connection with the accompanying drawings, of which Fig. 1 is a longitudinal section through a burner embodying one form of my invention.

Fig. 2 is a similar view illustrating another form of my invention.

Fig. 3 is a section on the line 3—3 of Fig. 1.

Fig. 4 is a section on the line 4—4 of Fig. 2.

Fig. 5 is an edge view of the latching member prior to being mounted on its pivot.

Referring to the drawings 10 indicates the usual wick tube in which there is an annular wick 11. On the interior of the wick tube there is a ledge 12 which supports the flame-spreader unit 13, the details of construction of this unit being immaterial except that there is provided a vertically extending rod 14 which has its upper end secured in the disc 15 and carries a horizontally arranged disc 16 on its lower end. A bail 17 is provided on the flame-spreader for conveniently lifting it out of the wick tube, the lower ends of this bail being formed with hooks 18 which engage in perforations in the tube 19 which forms a part of the unit. While I have shown the rod 14 for supporting the disc 16 other means of supporting this disc may be provided, although it is preferred that the disc 16 be so supported that the flame-spreader unit may be rotated within the wick tube.

A latching member for the flame-spreader unit is provided, this being in the form of a bell-crank lever 20 having a vertically extending arm 21 the upper end of which is formed with a hook 22 for engagement with the disc 16. There is also provided a cam surface 23 on the upper end of the arm 21 which cooperates with the edge of the disc 16 to move the arm 21 radially outward when the flame-spreader unit is inserted in the wick tube. The latch member 20 is piv-

oted on the fuel supply pipe 24, on which the wick tube 10 is mounted according to the usual practice. The member 20 has a horizontally extending arm or handle 25 which is arranged below the wick tube and serves as a means for moving the member 20 so as to disengage the hook 22 from the disc 16 to permit removal of the flame-spreader unit. The arm 25 also acts as a counter-weight whereby the force of gravity is utilized to normally hold the hook 22 in engagement with the disc 16, thus avoiding the necessity for springs or analogous devices to accomplish this purpose.

The latch member 20 is preferably stamped from sheet steel and, in order to permit it to be conveniently attached to the fuel pipe 24, the hub of the member 20 has a radial split 26 which permits the metal on opposite sides of the split to be bent, as shown at 27 and 28, in Fig. 5, so that the member 20 may be slipped over the fuel pipe and the portions 27 and 28 then bent back into the plane of the member 20.

In order to form a guide for the arm 21 and also a stop to limit its inward movement, when detached from the disc 16, I have provided the member 29 which has a radially extending portion comprising two folds between which the arm 21 is movable, as shown in Fig. 3. The member 29 is also provided with the arcuate portions 30 and 31 which fit on the interior of the wick tube and hold the member 29 in position.

In the form of the invention illustrated in Figs. 2 and 4 the guide for the arm 21 consists of an upright member 32 formed from a piece of sheet metal which is folded, as indicated at 33 to provide the space in which the arm 21 moves. The member 32 has an integral bracket 34 which is clamped on the fuel pipe by means of a bolt 35. In practice the member 32 and the bracket 34 may be formed integral.

Having thus described my invention, what I claim is:

1. In oil burners, the combination of a fuel supply pipe, a wick tube secured thereon, a removable flame-spreader supported within said wick tube, and a latch member pivoted on said pipe and engaging a part of said flame-spreader to releasably lock the flame-spreader in position.

2. In oil burners, the combination of a fuel supply pipe, a wick tube secured thereon, a removable flame-spreader supported

within said wick tube, a horizontally arranged disc carried by said flame-spreader in coaxial relation therewith, and a pivotally supported latch member cooperating with said disc to releasably lock the flame-spreader in position.

3. In oil burners, the combination of a fuel supply pipe, a wick tube secured thereon, a removable flame-spreader supported within said wick tube, a horizontally arranged disc carried by said flame-spreader in coaxial relation therewith, and a latch member pivoted on said pipe and cooperating with said disc to releasably lock the flame-spreader in position.

4. In oil burners, the combination of a wick tube, a removable flame-spreader supported within said wick tube and having a central rod with a horizontally arranged disc on its lower end, and a vertically arranged latch member movable radially of the wick tube by said disc when the flame-spreader is inserted in the wick tube and having means to engage the upper side of the disc to lock the flame-spreader in position.

5. In oil burners, the combination of a wick tube, a removable flame-spreader supported within said wick tube and having a central rod with a horizontally arranged disc on its lower end, a vertically arranged latch member movable radially of the wick tube by said disc when the flame-spreader is inserted in the wick tube and adapted to automatically engage the disc to lock the flame-spreader in position, and said latch member having a handle below the wick tube whereby said member may be disengaged from said disc to release the flame-spreader.

6. In oil burners, the combination of a wick tube, a removable flame-spreader supported within said wick tube and having a central rod with a horizontally arranged disc on its lower end, a latch member adapted to automatically engage said disc to lock the flame-spreader in position, and said latch member having a handle extending below the wick tube whereby said member may be disengaged from said disc to release the flame-spreader.

7. In oil burners, the combination of a wick tube, a removable flame-spreader supported within said wick tube, a fuel pipe on which the wick tube is supported, a latch member for the flame-spreader pivoted on said pipe, a guide for the latch member supported within the wick tube, and a handle on said latch member extending horizontally below the wick tube and actuated by gravity to effect the engagement of the latch member with the flame-spreader.

8. In oil burners, the combination of a wick tube, a removable flame-spreader supported within said wick tube, a fuel pipe below the wick tube, a vertically arranged bell-crank pivoted on said pipe and movable in a plane radial to the axis of the wick tube, said bell-crank having a vertical arm provided with means for engaging the flame-spreader to lock the latter in position, and a guide for said vertical arm having means to limit the movement of the bell-crank in one direction.

9. In oil burners, the combination of a wick tube, a removable flame-spreader supported within said wick tube, a fuel pipe below the wick tube, a vertically arranged bell-crank pivoted on said pipe and movable in a plane radial to the axis of the wick tube, said bell-crank having a vertical arm provided with means for engaging the flame-spreader to lock the latter in position, and a guide for said vertical arm carried by said pipe and having means to limit the movement of the bell-crank in one direction.

10. In oil burners, the combination of a wick tube, a removable flame-spreader supported within said wick tube, a fuel pipe below the wick tube, a vertically arranged bell-crank pivoted on said pipe and movable in a plane radial to the axis of the wick tube, said bell-crank having a vertical arm provided with means for engaging the flame-spreader to lock the latter in position, and a U-shaped guide for said vertical arm carried by said pipe.

In testimony whereof, I hereunto affix my signature.

RUDOLPH HOFFMAN.
